APPROACH LOCK RELEASE IN RAILWAY SIGNALING SYSTEMS

Ira F. Cadman, Swissvale, Pa., assignor to The Union Switch & Signal Company, Swissvale, Pa., a corporation of Pennsylvania

Application February 6, 1946, Serial No. 645,913

5 Claims. (Cl. 246—3)

1

My invention relates to railway signaling apparatus and has particular relation to the organization of railway signaling apparatus into systems for interlocking the control of signals governing traffic movements in opposite directions over a stretch of track. More specifically, my invention relates to systems of the type mentioned incorporating means for effecting the release of approach lock means in systems utilizing semaphore type railway signals.

It has been proposed heretofore to use as an approach relay for a signal governing traffic in a given direction over a stretch of track, the traffic controlled signal governing relay for the signal governing opposing traffic movements over the track, and to energize this traffic controlled signal governing relay momentarily under certain conditions in order to effect a release of the approach locking means for the given direction traffic controlling signal. An object of my invention is to provide means for utilizing this principle in signaling systems which employ semaphore type railway signals and which are inherently incapable of using the momentary energization of the traffic controlled signal governing relay directly in the control of the approach lock relay. Certain features included in the present application are disclosed in Letters Patent of the United States No. 2,369,113, granted to Earl M. Allen on February 13, 1945, and in a copending application Serial No. 501,254, filed on September 4, 1943, by Henry S. Young and assigned to the assignee of the present application, now Patent No. 2,420,579, granted May 13, 1947.

The above mentioned and other important objects and characteristic features of my invention are obtained by incorporating into a system of the type described which includes an approach locking relay for a given signal, a stick relay provided with a pick-up circuit including a contact of the momentarily energized traffic controlled signal governing relay for the opposing signal and a manually operable contact used in the control of the given signal, and with a stick circuit in which a front contact of the stick relay provides an alternate path around the contact of the momentarily energized traffic controlled signal governing relay; and by utilizing a contact of this stick relay in the circuit of the approach lock relay for the given signal. Other novel features of the invention will be pointed out in the following description.

I shall describe one form of apparatus embodying my invention, and shall then point out the novel features thereof in claims.

2

Referring to the accompanying drawings, Figs. 1a and 1b when placed end to end with Fig. 1a on the left constitute a single diagrammatic view of a preferred form of apparatus embodying my invention.

Referring to the drawings, the reference character M designates a stretch of track represented in a single-line diagrammatic form, which stretch of track is divided by the usual insulated joints 2 into a plurality of successive adjoining track sections designated by the reference character T with suitably distinguishing prefixes. Each of the track sections is provided in the customary manner with a track circuit including a track relay designated by the reference character R with a prefix corresponding to the designation of its associated track section, and a suitable source of current. In the diagrammatic representation of the track circuits in the drawing, 20 the association of each track relay with its associated circuit is indicated by a dotted line, and the connection of each battery to its associated circuit is indicated by a reference character B.

Sections 1T and 3T include track switches 1 and 3, respectively, which connect the rails of stretch M with the rails of a passing stretch P. It is to be understood, of course, that the rails of the turnouts including the track switches are included in the track circuit of the associated section up to the fouling point of each turnout, and each track switch has a normal position in which traffic is permitted to move along track M, and has a reverse position in which the switch operates to divert traffic from track M to track P or permits movement of traffic from track P to track M. Each track switch operates a circuit controlling contact 10 between a normal position and a reverse position and each track switch is provided with two switch position indicating relays, designated by the reference characters NW and RW with prefixes corresponding to the designation of the switch. These switch position indicating relays are controlled by contact 10 over obvious circuits in such manner that relay 3NW is energized when switch 3 is in its normal position and relay 3RW is energized when switch 3 is in its reverse position.

Traffic operating in the eastbound direction on stretch M, that is, from left to right as viewed in the diagram, is controlled by signals 2RA and 4RA, while traffic operating over switch 1 in the eastbound direction is governed by a signal 2RB and traffic in the eastbound direction over switch 3 is governed by a signal 4RB. Westbound traffic operating on track M is governed by

signals 4LA and 2LA, while westbound traffic over switch 3 is governed by signal 4LB and westbound traffic over switch 1 is governed by signal 2LB. These signals, as indicated in the diagram, are of the semaphore type and may be similar for example to the signal shown in Letters Patent of the United States No. 611,943, granted to J. G. Schreuder on October 4, 1898. Each signal is provided with an arm or semaphore blade having a 0° or stop position, a 45° or caution position, and a 90° or clear position, and each signal has a suitable operating mechanism for operating the associated blade to the positions mentioned.

The signals 4RA and 4LA govern traffic in opposite directions in section 3T and hence these signals may be considered as opposing signals. Signal 2RA governs traffic on track M approaching signal 4RA and may therefore be considered an approach signal for signal 4RA. Each of the signals illustrated in the drawing is controlled through the medium of home and distant relays in a manner corresponding to that illustrated in the drawing for the control of signal 4LA. When the associated home relay 4LAH is released, signal 4LA is deenergized and occupies its stop or 0° position; when relay 4LAH is picked up to close the front point of its contact *a*, signal 4LA is energized over an obvious circuit including the front point of that contact and is caused to operate to its caution or 45° position; and when relay 4LAH is picked up and distant relay 4LHD is operated to its reverse position, another element of signal 4LA becomes energized over the front contact of relay 4LAH and contact *a* of relay 4LHD closed in its reverse position, whereupon signal 4LA is caused to operate to its clear or 90° position.

Each of the signals is provided with circuit controlling contacts operated by the associated mechanism to occupy different positions according to the position of the semaphore blade. For example, signal 2LA illustrated in Fig. 1a is provided with contacts *a* and *b* operated by the mechanism of signal 2LA so that when the signal is in its stop position, its contacts *a* and *b* are in the positions illustrated in the drawing and remain in these positions until signal 2LA operates to its caution or 45° position. At or between its 45° and 90° (clear) positions contacts *a* and *b* are operated to the reverse positions indicated by dotted lines in the drawing. The signals are also provided with 0° position indication relays which correspond to relay 4RP provided for signals 4RA and 4RB. Relay 4RP is energized over an obvious circuit passing from one terminal B of a suitable source of current such as a battery not shown but having its opposite terminals designated by the reference characters B and C, through contact *a* of signal 2RA closed in the 0-45° position of that signal, contact *a* of signal 4RB closed in its 0° position, contact *a* of signal 4RA closed in its 0° position and the winding of relay 4RP to terminal C. The control of the relay 4RP is such that the relay is deenergized whenever signal 4RA or 4RB operates from its 0° (stop) position, or whenever signal 2RA operates beyond its 45° (caution) position to its 90° (clear) position. Relay 4LP is similarly controlled by signals 4LA, 4LB, and the signal (not shown) in approach to signal 4LA.

It is contemplated that the signals and switches shown in the drawing are controlled from a remote office through the medium of a communication system of the centralized traffic control

type. The system may for example be of the type shown in Letters Patent of the United States No. 2,229,249, granted to Lloyd V. Lewis on January 21, 1941, but modified to correspond with the showing of Letters Patent of the United States No. 2,197,130, granted to Lloyd V. Lewis on April 16, 1940, this modification providing for arrangements to enable the switch control relay 3WS and signal control relays 4RHS and 4LHS to be of the stick polar type, as shown in Fig. 1b, all of these relays being of the stay-where-put type arranged to be held in their last operated positions when deenergized. Each of the switch and signal control relays has a normal position in which its polar armature is operated to its left-hand position, as viewed in the drawing, and a reverse position in which its polar armature is operated to its right-hand position.

The switch control relay 3WS controls a power-operated switch mechanism (not shown) for effecting operation of switch 3 by power in response to control from the remote office, and also cooperates with the switch indicating relays 3NW and 3RW to control switch correspondence relays 3NWC and 3RWC in such a manner that relay 3NWC is energized over an obvious circuit including the front point of contact *a* of relay 3NW and contact *a* of relay 3WS in its normal position, while relay 3RWC will be energized when contact *a* of relay 3RW is closed in its front position and contact *a* of relay 3WS is operated to its reverse position.

Relay 4RHS cooperates with distant relay 4LHD of signal 4LA to control an approach relay 4RAR over a circuit including contact *a* of relay 4RHS closed in its normal position, contact *b* of relay 4LHD closed in its front position and the winding of relay 4RAR to terminal C. When relay 4RAR picks up, its contact *a* is operated to its front position to close an alternate path in the circuit for this relay around contact *b* of relay 4LHD, and this alternate stick circuit path holds relay 4RAR energized in the event that relay 4LHD releases while contact *a* of relay 4RHS is retained in its normal position.

The reference character 4LAR designates another approach relay controlled over a circuit indicated conventionally in the drawing as including a contact *x* which represents the inclusion of front contacts of all track relays of the track sections between signal 4LA and its approach signal (not shown).

The reference character 4AS designates a control relay for controlling a time element relay TE over an obvious circuit including the front point of contact *a* of relay 4AS. Relay 4AS is energized over a circuit including contact *a* of relay 3TR closed in its front position and then passing through one or another of two alternate paths, one path including contact *a* of approach locking relay 4RAS closed in its back position, front contact *a* of relay 4RP and contact *b* of relay 4RHS closed in its normal position; and the other path extending through contact *a* of approach locking relay 4LAS closed in its back position, front contact *a* of relay 4LP and contact *a* of relay 4LHS closed in its normal position.

The approach locking relay 4RAS is provided with an energizing circuit extending from terminal B through contact *b* of relay 4RHS closed in its normal position, contact *a* of relay 4RP closed in its front position, contact *b* of relay 4RAR closed in its front position, contact *a* of relay 3NWC closed in its front position and the winding of relay 4RAS to terminal C. As is

customary, relay 4RAS is provided with a track circuit release in which contact *b* of relay 3TR closed in its back position provides an alternate path around contacts *b* of relay 4RAR and *a* of relay 3NWC. Relay 4RAS is also provided with a time release circuit in which contact *a* of time element device 4TE, which is closed to its front point at the expiration of a predetermined time interval after the energization of relay 4TE, also provides an alternate path in the circuit for relay 4RAS around contacts *b* of relay 4RAR and *a* of relay 3NWC. Relay 4RAS is further provided with a stick circuit in which its front contact *a* provides an alternate path around the track circuit release, time release, and approach relay controlled paths.

Approach locking relay 4LAS is controlled by relays 4LHS, 4LP, 4LAR, 3TR, and 4TE in a manner corresponding to that described for the control of relay 4RAS, as will be apparent from an inspection of the drawing.

The approach locking relays 4RAS and 4LAS are employed in the usual manner to provide locking between the opposing signals 4RA and 4LA so arranged as to permit signal 4RA to be cleared only when relay 4LAS is picked up, and signal 4LA to be cleared only when relay 4RAS is picked up. The relays 4RAS and 4LAS also control the operation of switch 3, the arrangement being such that switch 3 may be controlled by switch relay 3WS, which is operated from the C. T. C. office through the communication system, when relays 4RAS and 4LAS are both picked up. The apparatus for effecting control of switch 3 is not shown in the drawing since it is well known in the art, but it will be understood, of course, that the interlocking circuits at the field station are such that switch 3 must be in a proper position before either signal 4RA or 4LA is cleared. The arrangement of the apparatus is thus such that all possible routes over a switch are available to an operator only when both approach locking relays at that location are picked up and in this condition of the apparatus the approach locking is considered released.

A block repeating or route relay 4BP also is provided and is controlled in the same manner as that shown for relay 2BPR in the previously mentioned Young Patent No. 2,420,579, by a circuit governed by the detector track relay 3TR, switch correspondence relays 3NWC and 3RWC, distant control relays 4LHD and 4RHD provided for signals 4LA and 4RA respectively, and by signal control relays 4LHS and 4RHS. When relay 4RHS is reversed preparatory to clearing signal 4RA, relay 4BP becomes energized provided traffic and track conditions are proper for signal 4RA to clear, over a circuit from terminal B at contact *c* of relay 4LHS in its normal position, contact *d* of relay 4RHS in its reverse position, front contact *a* of distant control relay 4RHD provided for signal 4RA, contact *c* of relay 3RWC in its back position, contact *d* of relay 3NWC in its front position, front contact *c* of relay 3TR and the winding of relay 4BP to terminal C. Relay 4RHD is controlled in accordance with the usual practice by the track circuits that intervene between signal 4RA and the signal (not shown) in advance of signal 4RA, and by that advance signal, so as to be energized only when conditions are proper for signal 4RA to be cleared. If relay 4LHS is reversed and conditions are proper for signal 4LA to clear, relay 4BP is provided with a circuit from terminal B at contact *d* of relay 4RHS in its normal position through contact *c*

of relay 4LHS in its reverse position, front contact *c* of the distant control relay 4LHD provided for signal 4LA, back contact *c* of relay 3RWC, front contact *d* of relay 3NWC, front contact *c* of relay 3TR and the winding of relay 4BP to terminal C. With relay 4LHS and switch 3 reversed, alternate paths in the last traced circuit for relay 4BP are provided in which front contact *d* of relay 3RWC is connected around front contact *c* of relay 4LHD; and back contact *d* and front contact *c* of relays 3NWC and 3RWC replace back contact *c* of relay 3RWC and front contact *d* of relay 3NWC respectively.

The home signal control relays 4RAH, 4RBH, 4LAH and 4LBH provided respectively for signals 4RA, 4RB, 4LA and 4LB are controlled by relays 4RHS and 4LHS in cooperation with the route relay 4BP and approach locking relays 4RAS and 4LAS, with selection between the signals 4RA or 4RB and 4LA or 4LB being determined by the position of switch 3 as reflected by the switch correspondence relays 3NWC and 3RWC. The circuit for relay 4LAH or relay 4LBH passes from terminal B through contact *a* of relay 4LHS in its reverse position, contact *a* of relay 4BP in its front position, contact *b* of relay 4RAS in its front position, contact *b* of relay 4TE in its back position, contact *b* of relay 4LAS in its back position and either contact *b* of relay 3NWC closed in its front position and the winding of relay 4LAH, or contact *a* of relay 3RWC in its front position and the winding of relay 4LBH, and then extending through contact *b* of relay 4LHS in its reverse position and contact *c* of relay 4RHS in its normal position to terminal C. Similarly, relay 4RAH or 4RBH is energized over a circuit extending from terminal B through contact *b* of relay 4RHS closed in its reverse position, contact *b* of relay 4BP closed in its front position, contact *b* of relay 4LAS in its front position, contact *b* of relay 4TE in its back position, contact *b* of relay 4RAS in its back position, and either contact *c* of relay 3NWC and the winding of relay 4RAH, or contact *b* of relay 3RWC and the winding of relay 4RBH, and then extending through contact *c* of relay 4RHS closed in its reverse position and contact *b* of relay 4LHS closed in its normal position to terminal C.

The distant control relay 4LHD for signal 4LA is controlled over a circuit passing from terminal B through contact *b* of signal 2LA closed in its 0°-45° position, the winding of relay 4LHD, contact *a* of relay 4TR in its front position, contact *a* of relay 2TR in its front position, contact *a* of relay 1TR in its front position, contact *a* of relay 2RAS in its front position and contact *a* of signal 2LA closed in the 0°-45° position of that signal to terminal C. An alternate path including contact *a* of relay 1RWC closed in its front position is provided around contacts *a* of relays 1TR and 2RAS in the circuit just traced, while another alternate path including contact *a* of relay 2RHD closed in its normal position, contact *a* of a relay 2RD (hereinafter referred to) closed in its front position and contact *a* of relay 0TR closed in its front position is provided around contact *a* of relay 2RAS in the circuit first traced for relay 4LHD. The contacts *a* and *b* of signal 2LA operate as pole changing contacts to control in accordance with the position of signal 2LA, the polarity of current supplied to relay 4LHD over the circuit just traced, as is apparent from an inspection of the drawing.

The distant control relay 2RHD of signal 2RA is controlled by a circuit which is correspondingly similar to the circuit for relay 4LHD as will be apparent from an inspection of the drawing.

Relay 2RD is a slow releasing repeater of relay 2RHD in its operated i. e. right-hand-position and is controlled over a circuit passing from terminal B through contact b of relay 2RHD closed in its front position, contact c of relay 2RHD closed in its reverse position and the winding of relay 2RD to terminal C. When contact c of relay 2RHD is operated to its normal position, relay 2RD is provided with a short circuit path connected across its terminals and through which current circulates during the decay of flux in relay 2RD to snub the release of that relay. Relay 4LD is a repeater of relay 4LHD in its operated position and is controlled by relay 4LHD in a manner corresponding to the control of relay 2RD by relay 2RHD as will be obvious from an inspection of the drawing.

Relay 2RAS which has a contact interposed in a circuit path traced for relay 4LHD, is controlled by relay 2RHS through circuits (not shown) similar to the circuits traced for the control of relay 4LAS by relay 4LHS but involving apparatus provided at the other end of passing track P. Relay 4RWC is controlled by switch 1 and its related control apparatus in a manner corresponding to the control of relay 3RWC by the circuits traced for the latter relay.

I shall now describe the manner of operation of the apparatus embodying my invention. In the description I shall assume that the stretches of track M and P, within the limits of the sections represented in the drawing, are vacant; that track switches 1 and 3 occupy their normal positions; and that all of the signals represented in the drawing are in their stop or 0° positions. In this condition of the apparatus as represented in the drawing, all track relays are picked up; remotely controlled switch operating relay 3WS and signal operating relays 4RHS and 4LHS are in their normal or left-hand positions; normal position indicating relay 3NW and switch correspondence relay 3NWC are picked up; approach relays 4RAR and 4LAR are picked up; signal repeating relays 4RP and 4LP are energized; approach locking relays 4RAS, 4LAS and 2RAS are picked up; distant control relays 4LHD and 2RHD are energized in their normal directions so that their contacts occupy their left-hand positions respectively; relay 4RHD is energized; and all other relays represented in the drawing are released.

I shall now assume that the operator clears signal 4RA by manipulation of the controlling lever of the communication system in the central office to cause relay 4RHS to operate its contacts to their reverse or right-hand positions. When this happens, contact d of relay 4RHS closes in its reverse position to energize relay 4BP over its previously traced circuit; relays 4RAR and 4RAS become deenergized; and relay 4RAH becomes energized over its previously traced circuit including contact b of relay 4RHS closed in its reverse position, front contact b of relay 4BP, front contact b of relay 4LAS and back contact b of relay 4RAS. The energization of relay 4RAH results in the closing of its contact a to its front position so that signal 4RA operates to its caution position. It is understood, of course, that distant relay 4RHD provided for signal 4RA controls the operation of that signal to its clear

position under certain conditions, but the control of the signal by this relay and the control of the distant relay itself are not shown in order to avoid unnecessary complication of the drawing.

The operation of signal 4RA to its caution position results in the opening of contact a of signal 4RA to deenergize relay 4RP, and in the operation of contacts b and c of signal 4RA to their reverse positions to reverse the polarity of energization of relay 2RHD which thereupon operates its polar armature to its right-hand position. Relay 2RD now becomes energized, and the contact of relay 2RHD in its reverse position conditions signal 2RA to operate to its clear position should signal 2RA be controlled from its stop position by the operator from the C. T. C. office through the medium of relay 2RHS represented in the drawing.

If the operator clears signal 2RA through the medium of the actuation of the proper signal controlling lever at the C. T. C. office, relay 2RAH will be picked up through circuits and related apparatus which correspond to the circuits shown in Fig. 1b for relay 4RAH, and with relay 2RHD reversed, signal 2RA will be operated to its clear position. Contact a of signal 2RA in the circuit of relay 4RP is now opened, and contact a of relay 2RAS in the circuit of relay 4LHD also is opened because relay 2RAS becomes deenergized in the control of relay 2RAH in a manner corresponding to the release of relay 4RAS in the control of relay 4RAH. Relay 4LHD therefore becomes deenergized.

If, now, the operator restores both signals 2RA and 4RA to their stop positions by manipulation of the levers controlling relays 2RHS and 4RHS, before a train in the east-bound direction enters the stretch of track within the limits of the sections represented in the drawing, the apparatus illustrated in the drawing will operate in the usual manner to pick up approach locking relay 4RAS and thus release the locking between the opposing signals. That is to say, signal 4RA going to stop closes its contact a in the circuit of relay 4RP, and reverses the positions of contacts b and c in the circuit of relay 2RHD so that relay 2RHD is operated to its normal position. Signal 2RA will be put to stop through the deenergization of relay 2RAH and under the conditions assumed, relay 2RAS will be picked up to close its contact a in the circuit of relay 4LHD. Contact a of relay 4RHS will be operated to its normal position, so that when relay 4LHD picks up and closes its contact b in the circuit of relay 4RAR, relay 4RAR picks up to close its contact b in the circuit of relay 4RAS, and relay 4RP also picks up to close its contact a in the circuit for relay 4RAS, with the result that the approach locking relay 4RAS picks up. However, if with signals 2RA and 4RA cleared, the operator restores relay 4RHS to its normal position to place relay 4RA to stop without restoring relay 2RHS to its normal position to place signal 2RA to stop at the same time, the following operation takes place. Relay 4RAH releases since its circuit is now open at contact b of relay 4RHS, signal 4RA thereupon operates to its 0° position and at its 45° position its contacts b and c are reversed to reverse the polarity of energization of relay 2RHD. This closes contact a of relay 2RHD in the circuit of relay 4LHD, and also operates contact c of relay 2RHD to its normal position to deenergize relay 2RD and provide the short circuit path around its winding. Relay 4LHD now

becomes momentarily energized during the slow release time of relay 2RD over its circuit including contact *a* of relay 2RHD and contact *a* of relay 2RD; and front contact *b* of relay 4LHD accordingly completes the pick-up circuit of relay 4RAR. Contact *a* of relay 4RAR closes to complete the stick circuit path around contact *b* of relay 4LHD, and when the latter relay releases at the end of the slow release period of relay 2RD, the stick circuit of relay 4RAR holds the relay 4RAR energized. At this time, of course, relay 2RAS which has a front contact normally closed in the circuit of relay 4LHD, is released due to the fact that relay 2RHS for signal 2RA is in its reverse position.

The reversal of relay 2RHD results in signal 2RA going to its caution or 45° position at which position contact *a* of signal 2RA closes, while operation of signal 4RA to its stop position results in contact *a* of that signal closing in its 0° position. The operation of the signal contacts *a* of signals 2RA and 4RA to the positions in which they close to complete the energizing circuit for relay 4RP, takes an appreciable length of time, much longer than the time that relay 2RD holds its front contact *a* closed. As a result, therefore, relay 4RP does not pick up to close its front contact *a* during the interval that relay 4LHD is energized over the slow releasing front contact of relay 2RD so that but for the introduction of front contact *b* of the stick relay 4RAR in the circuit of relay 4RAS, the momentary energization of relay 4LHD could not be used in the control of the approach locking relay 4RAS. However, relay 4RAR is picked up by the momentary energization of relay 4LHD, and is held picked up over its stick circuit after relay 4LHD releases so that when relay 4RP subsequently picks up, the pick-up circuit of relay 4RAS can be established and that relay accordingly picks up.

With relay 4RAS picked up in the manner described, and relay 4LAS also in its picked-up position, the approach locking is released and the operator is now in a position to select any one of the routes over switch 3.

From the foregoing description it is apparent that distant relay 4LHD for one of the opposing signals 4LA, is momentarily energized to effect the release of the approach locking provided for the other opposing signal 4RA. This momentary energization of relay 4LHD is effected when signal 4RA is put to stop while signal 2RA is held out of its stop position, and is effected through the operation of contacts of signal 4RA to their reverse position when signal 4RA reaches its 45° or caution position. At the time that the contacts *b* and *c* of signal 4RA reverse to reverse the energization of the distant relay 2RHD for the approach signal 2RA, relay 4LHD becomes momentarily energized during the interval that relay 2RD operated by relay 2RHD holds its front contacts closed, and this momentary energization of relay 4LHD closes the pick-up circuit of a stick relay 4RAR, which relay in turn closes its front contact to provide a stick circuit path around the front contact of relay 4LHD so as to maintain relay 4RAR picked up after relay 4LHD releases. This pickup of relay 4RAR stores the momentary energization of relay 4LHD so that after the signal repeating relay 4RP is picked up at the end of the appreciable time interval required for the contacts of signal 4RA to close in their 0° or stop position, and the contacts operated by signal 2RA to close in their 45° position, the pick-up circuit for approach locking re-

lay 4RAS may be completed over a contact of relay 4RAR.

The apparatus of my invention is therefore arranged to provide means for utilizing the momentary energization of a distant relay in the control of the approach locking relay for an opposing signal in a signaling system which incorporates semaphore type signals and which is inherently incapable of using the momentary energization of the distant relay directly in the control of the approach lock relay.

Apparatus also has been illustrated in the drawing to provide approach control relay 4RAS with a track circuit release controlled by relay 3TR, and a time release controlled by element 4TE. This apparatus is represented to show a complete operative system for the control of relay 4RAS, but a description of the operation of this apparatus is believed to be unnecessary since it operates in a manner well known in the art.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In a railway signaling system for a stretch of railroad track provided with two opposing signals and an approach signal for one of said opposing signals, said signals being of the semaphore type having stop, caution and clear positions and having contacts selectively operated in accordance with the position of said signal, the combination with a signal control contact operable to a position for clearing said one opposing signal and having another position, an approach locking relay for said one opposing signal for controlling over its front contact the clearing circuit for the other opposing signal, means controlled by contacts of said one opposing signal for operating said approach signal from caution to clear, a signal repeating relay controlled by said signal operated contacts to be energized only when said one opposing signal is at stop and said approach signal is either at or between its stop and caution positions, a distant control relay for said other opposing signal momentarily energized when said approach signal operates from its clear to its caution position when said stretch between said approach and said one opposing signal is vacant, of an approach relay provided with a pick-up circuit including a front contact of said distant control relay and a contact operated in synchronism with said signal control contact, a stick circuit for said approach relay including its front contact connected around the contact of said distant control relay, and a circuit for said approach locking relay including a front contact of said signal repeating relay and said signal control contact in said other position.
2. In a railway signaling system for a stretch of railroad track provided with two opposing signals and an approach signal for one of said opposing signals, said signals being of the semaphore type having stop, caution and clear positions and having contacts selectively operated according to the position of said signal, the combination with a signal control contact operable to one position for clearing said one opposing signal and having another position, an approach locking relay for said one opposing signal for con-

trolling over its front contact the clearing circuit for the other opposing signal, a signal repeating relay controlled by said signal operated contacts to be energized only when said one opposing signal is at stop and said approach signal is either at or between its stop and caution positions, a distant control relay for said other opposing signal momentarily energized when said approach signal operates from its clear to its caution position when said stretch between said approach and said one opposing signal is vacant, and means controlled by contacts of said one opposing signal for operating said approach signal between its caution and clear positions, of means controlled by said distant control relay for storing the momentary energization of that relay during the interval required by the contacts of the semaphore signals to operate between the clear and stop positions of said one opposing signal, and a circuit for said approach locking relay including said signal control contact in its said other position and a front contact of said signal repeating relay and controlled by said storing means to be completed after release of said distant control relay.

3. In a railway signaling system for a stretch of railroad track provided with a first signal governing traffic in one direction in said stretch, a second signal governing traffic in the opposite direction in a portion of said stretch governed in one direction by said first signal, and a third signal governing traffic in said one direction approaching said first signal, said signals being of the semaphore type having stop, caution and clear positions and characterized by requiring appreciable intervals of time to operate from one position to another and having contacts selectively operated according to the position of the signal, the combination with a signal control contact operable to one position for clearing said first signal and having another position, an approach locking relay for said first signal for controlling over its front contact the clearing circuit for said second signal, means controlled by contacts of said first signal in its caution position for operating said third signal from its caution to its clear position, a signal repeating relay controlled by said signal operated contacts to be energized only when said first signal is at stop and said third signal is either at or between its stop and caution positions, a distant control relay for said second signal momentarily energized when said third signal operates from its clear to its caution position when said stretch between said third and said first signal is vacant, of an approach relay provided with a pick-up circuit including a front contact of said distant control relay and a contact operated in synchronism with said signal control contact, a stick circuit for said approach relay including its front contact connected around the contact of said distant control relay, and a circuit for said approach locking relay including a front contact of said approach relay, a front contact of said signal repeating relay and said signal control contact in said other position.

4. In a railway signaling system for a stretch of railroad track provided with a first signal governing traffic in one direction in said stretch and a second signal governing traffic in said one direction approaching said first signal, said signals being of the semaphore type having stop, caution and clear positions and characterized by requiring appreciable intervals of time to operate

from one position to another and having contacts selectively operated according to the position of the signal, the combination with a signal control contact operable to one position for clearing said first signal and having another position, an approach locking relay for said first signal, means controlled by contacts of said first signal in its caution position for operating said second signal from its caution to its clear position, a signal repeating relay controlled by said signal operated contacts to be energized only when said first signal is at stop and said second signal is either in or between its stop and caution positions, another relay momentarily energized when said second signal operates from its clear to its caution position when said stretch between said second and said first signal is vacant, of an approach relay provided with a pick-up circuit including a front contact of said other relay and a contact operated in synchronism with said signal control contact, a stick circuit for said approach relay including its front contact connected around the contact of said other relay, and a circuit for said approach locking relay including a front contact of said approach relay, a front contact of said signal repeating relay and said signal control contact in said other position.

5. In a railway signaling system for a stretch of railroad track provided with two opposing signals and an approach signal for one of said opposing signals, said signals being of the semaphore type having stop, caution and clear positions and having contacts selectively operated in accordance with the position of the signal, the combination with manually controllable means having contacts operable between a position for clearing said one opposing signal and another position, an approach locking relay for said one opposing signal for controlling over its front contact the clearing circuit for the other opposing signal, means controlled by contacts of said one opposing signal in its caution position for operating said approach signal from its caution to its clear position, a signal repeating relay controlled by said signal operated contacts to be energized only when said one opposing signal is at stop and said approach signal is either in or between its stop and caution positions, a distant control relay for said other opposing signal momentarily energized when said approach signal operates from its clear to its caution position when said stretch between said approach and said one opposing signal is vacant, of an approach relay provided with a pick-up circuit including a front contact of said distant control relay and a contact operated in synchronism with said signal control contact, a stick circuit for said approach relay including its front contact connected around the contact of said distant control relay, and a circuit for said approach locking relay including a front contact of said approach relay, a front contact of said signal repeating relay and said signal control contact in said other position.
